UNITED STATES PATENT OFFICE.

JAKOB SKANDORA, OF RACINE, WISCONSIN.

COAL-CAR.

1,220,018.

Specification of Letters Patent. Patented Mar. 20, 1917.

Application filed July 3, 1916, Serial No. 107,389. Renewed February 18, 1917. Serial No. 145,388.

To all whom it may concern:

Be it known that I, JAKOB SKANDORA, a subject of the King of Hungary, residing at Racine, in the county of Racine and State of Wisconsin, have invented certain new and useful Improvements in Coal-Cars, of which the following is a specification.

The primary object of this invention is the provision of a strong car adapted for 10 coal mines, coke furnaces or general use, the construction being such as to provide great rigidity for the wheel bearings and car body support.

A further object of the invention is to 15 provide a running gear for cars having a long axle bearing imparting great strength to the car and arranged with an advantageous support for the car body.

With these general objects in view and 20 others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:—

30 Figure 1 is a top plan view of the present form of running gear construction for a car adaptable for general use.

Fig. 2 is an end elevation thereof with the car body supported thereon and partially broken away.

Fig. 3 is an enlarged detail view of a corner portion of the same partly in section.

Fig. 4 is an inverted perspective view of a corner portion of the main plate of the 40 frame.

Fig. 5 is a perspective view of an end portion of one of the bottom journal plates employed with the main plates.

Fig. 6 is a perspective view of one of the 45 mounting brackets employed for the car body.

Fig. 7 is a top plan view of the main plate of a running gear frame adapted for coke furnace ovens, and,

50 Fig. 8 is a top plan view of the separate upper journal plates of a running gear frame adapted for coal cars.

It being understood that the invention resides in the provision of a running gear 55 for cars provided with mounting brackets for the car bodies, the invention broadly

consists of a centrally contracted main or upper journal plate 10 for the car frame arranged for journaling the wheel axles 11 transversely of the opposite ends thereof by cooperating with lower journal plates 12 secured thereto, the said main plate being provided with U-shaped brackets 13 adjacent the axles 11 for mounting the car body 14 thereon.

The journaling head 15 at each end of the main plate 10 has its journaling groove 16 resting upon the axles 11, a substantially semi-circular flange 17 being arranged at each end of the beads 15 with a receiving 65 socket 18 of greater diameter than the groove 16 and adapted to overlie and journal an annular shoulder 19 of the axle. The usual form of flanged track wheels 20 are secured to the axles 11 outwardly of the 70 flanges 17.

The lower journal plates 12 are provided with longitudinal receiving grooves 21 for inclosing the lower sides of the axles 11, the said journal plates 12 being secured to the 75 main plate 10 for journaling the axles 11 therebetween by means of bolts 22.

The U-shaped body mounting brackets 13 are positioned upon the main plate 10 adjacent the beads 15 being maintained upright 85 by means of an inwardly arranged series of securing bolts 23 while the said brackets are provided with shoulders 23 upon which the car body 14 is positioned and secured by means of bolts 24. Grease cups 31 are carried by the beads 15 for lubricating the 90 axles 11.

In Fig. 7 of the drawing a form of main plate 25 is illustrated especially designed for coke furnace cars and having journaling 95 beads 26 at its opposite ends for receiving the wheel axles (not shown) in substantially the same manner as the construction shown in Fig. 1, it being understood that similar lower journaling plates and body mounting 100 brackets are provided therefor. A central opening 27 is provided in the plate 25 adapted to allow the coke to pass therethrough into the furnace positioned therebeneath in the usual manner, corner reinforcing plates 28 being provided for the said 105 openings.

Fig. 8 illustrates a construction designed for coal cars and in which opposite journal plates 29 are provided connected together by a pivoted link 30, the said plates each having a longitudinal journaling bead 30 for

mounting upon the wheel axles (not shown), it being understood that similar lower plates are employed with the plates 28 secured thereto in any desired manner.

5 A strong running gear for cars adapted to be moved upon a track is thus arranged, the construction being easy and inexpensive to manufacture.

I claim:

10 A car running gear comprising a main upper plate having transverse beads at its opposite ends arranged with journaling grooves on their under sides and having semi-circular flanges at the ends of the said 5 grooves with journaling sockets of greater diameter than the said grooves, lower jour-

nal plates having longitudinal bodies provided with journaling grooves co-operatingly secured beneath the said main plate adjacent the grooves of the latter, axles journaled within the said grooves having annular shoulders journaled within the said flange sockets, wheels secured to the opposite ends of the said axles adjacent the said flanges, lubricating means for the said axles 25 carried by the upper plate beads, and U-shaped brackets transversely secured to the said upper plate adjacent to and inwardly of the said beads thereof and having car body receiving angular shoulders. 30

In testimony whereof I affix my signature.

JAKOB SKANDORA.
